US00D622149S

(12) **United States Design Patent**
Bernstein et al.

(10) **Patent No.:** **US D622,149 S**
(45) **Date of Patent:** **** Aug. 24, 2010**

(54) **FLUID CONTAINER**

(75) Inventors: **Bruce Bernstein**, Tampa, FL (US);
Rebecca Bernstein, Tampa, FL (US);
David McDonald, Merrimack, NH (US);
Jonathan Marks, Somerville, MA (US);
Jon Dixon, Nashua, NH (US)

(73) Assignee: **Relaj, Inc.**, Tampa, FL (US)

(**) Term: **14 Years**

(21) Appl. No.: **29/316,180**

(22) Filed: **Aug. 31, 2009**

(51) **LOC (9) Cl.** **09-01**

(52) **U.S. Cl.** **D9/526; D9/540**

(58) **Field of Classification Search** **D9/516, D9/520, 523, 525, 526, 527, 528, 529, 530, D9/537, 538, 539, 540, 549, 550, 551, 552, D9/571, 575, 682, 685, 686, 688, 690, 693, D9/723, 724, 215/381-385**

See application file for complete search history.

Primary Examiner—Stella M Reid*Assistant Examiner*—Elizabeth J Osweeki(74) *Attorney, Agent, or Firm*—Frijouf, Rust & Pyle, P.A.(57) **CLAIM**

The ornamental design for a fluid container, as shown and described.

DESCRIPTION

FIG. 1 is a front perspective view of a fluid container showing our new design;

FIG. 2 is a rear perspective view thereof;

FIG. 3 is a front view thereof;

FIG. 4 is a rear view thereof;

FIG. 5 is a right side view of FIG. 3;

FIG. 6 is a left side view thereof;

FIG. 7 is a top view thereof; and,

FIG. 8 is a bottom view thereof.
